UNITED STATES PATENT OFFICE.

GEORGE H. ELLIS, OF CHICAGO, ILLINOIS, ASSIGNOR TO INTERNATIONAL HARVESTER COMPANY, A CORPORATION OF NEW JERSEY.

FEEDING MECHANISM FOR FLAX-BRAKES.

No. 806,650.

Specification of Letters Patent.

Patented Dec. 5, 1905.

Application filed October 15, 1904. Serial No. 228,494.

To all whom it may concern:

Be it known that I, GEORGE H. ELLIS, a citizen of the United States, residing at Chicago, in the county of Cook and State of Illinois, have invented a new and useful Improvement in Feeding Mechanism for Flax-Brakes, of which the following is a complete specification.

While this invention is designed to be used in connection with flax-brakes and is shown applied thereto, it is also available for use on similar machines in which a uniform supply of straw is required.

The object in view is to furnish improved means for presenting a uniform flow of straw to the breaking and scutching mechanism regardless of the possible excess in the quantity placed upon the feed-table. The said means are designed with a view to making them more simple in construction, more efficient in operation and economical in manufacture than devices heretofore provided for such purposes.

With these and other objects in view the invention consists in providing two opposed needles having a gap therebetween, the said points being arranged and operated in a manner which will cause them to traverse the straw passage-way, through which the material is fed to the machine. The straw is made to bear yieldingly against the needle-points, while the extent of the gap, the rapidity with which it traverses said passage-way, and the pressure of the straw against the needle-points are all factors which will determine the amount of material delivered to the machine.

While the opposing needle-points might be attached to a continuously-rotating member or to any other suitable means which could be arranged to traverse the straw passage-way, the preferred form of the invention is set forth in the accompanying drawings, in which—

Figure 1 represents a side elevation of the feed end of a flax-breaking machine in which is embodied my improved feeding mechanism. Fig. 2 is a transverse section of same, taken as indicated by the line 2 2 in Fig. 1 and showing the relative position of the needle, the feeding-table, the feed-chain drive, the straw-receiving mechanism in the rear of the needle, and other parts. Fig. 3 is a partial longitudinal section of the machine,

taken adjacent to the needle and the toothed feeding-wheel, as indicated by the line 3 3 in Fig. 2. Fig. 3^a is an enlarged view of that portion of Fig. 3 which shows the delivery end of the straw passage-way, the needle-points, and the toothed feeding-wheel adjacent thereto. This view is designed to show the manner in which the straw is pressed against the needle-points and forced through the gap between said points. Fig. 4 illustrates the construction of the friction-clutch on the driving-shaft of the feed-chain, the view being partly in section and taken longitudinally with respect to said shaft. Fig. 5 is a detail perspective of one of the needle-points. Fig. 6 is a side elevation of one of the fingers of the feed-chain. Fig. 7 is a plan view of same, and Fig. 8 is a transverse section showing in detail the preferred construction of the links of the grasping-chain.

Referring to the drawings, A designates the rectangular frame of the machine, which consists, preferably, of angle-irons, the angles 1 forming the longitudinal sills, the angles 2 the vertical members, and the angles 3 the transversely-extending members of the frame. In suitable bearings on the frame A is journaled the transversely-extending shaft 4, on which is mounted the hexagonal-shaped sprocket-wheel 5, this sprocket-wheel supporting the forward or engaging end of the grasping and feeding chain 6. This grasping-chain 6 moves in the direction indicated by the arrows in Fig. 1, its function being to convey the material through the machine in order that it may be operated upon by the scutcher 7 and the breaking mechanism, which is not pertinent in this connection, and hence not shown. The grasping-chain consists of a series of rectangular-shaped links provided on their straw-engaging surfaces with two rows of teeth 6', bilaterally arranged, as shown in Fig. 8, with two intervening grooves 6'', these grooves fitting upon corresponding ways 6''' on the guide 6⁴.

Arranged in front of the machine is the feed-table 8, on the frame of which, in suitable bearings, are journaled the shafts 9 and 9'. To these shafts are rigidly secured the sprocket-wheels 10 and 10', respectively, about which is placed the feeding-chain 11. Pivotal secured to the special links 11' of the said feeding-chain, these special links being placed at suitable intervals, are the fin-

gers 11², which are provided with the tappets or cam projections 11³. The cam projections 11³ engage the guides 12 (see Fig. 2) on the feed-table and hold the said fingers rigid 5 while so engaged; but on leaving the guides the fingers are free to turn on their pivotal bearings, as shown in Fig. 1, and thus disengage themselves from the straw which has been pressed in front of them. This arrangement 10 also enables the feeding-chain to be extended to a position nearer the end of the table, and hence closer to the needle frame B, since the fingers can assume a non-interfering position when passing around the forward sprocket-wheel 10.

To insure a uniform pressure of the straw against the points of the needle B, the driving-shaft 9 for the feed-chain is provided with a friction-clutch, as shown in Fig. 2 and in 20 enlarged detail in Fig. 4. The disk 13 is rigidly secured to the shaft 9 by a set-screw 13' or other suitable means, while the opposing disk 14 is sleeved loosely upon said shaft. The driving-pulley 15 is rigidly secured to 25 the hub of the loosely-mounted disk 14 by means of set-screws, as shown, the collar 16 bearing against the hub of the disk. The leather disk 14', secured to the surface of the disk 14, provides proper contacting 30 surface for the friction-drive. A coil-spring 17 is placed on the end of the shaft 9 and made to bear against said collar. A second collar 18 bears against the outer end of the coil-spring, as shown. The hand-lever 19 is pivotally mounted on the bracket 20, with its pivotal point at 20', and is provided 35 with the slot 19' at its upper end, which engages said driving-shaft and bears against the collar 18, thus affording means for regulating the pressure between the disks 13 and 14. The lever 19 is held in position and 40 controlled by a series of notches 21' in the plate 21, the free end of the lever being held into said notches by means of the spring-rod 22. 45 By regulating the pressure between the disks in this manner the pressure between the straw and the points of the needles can be adjusted to the proper degree and the desired amount of straw be made to pass 50 through the gap in the needle-frame B.

Above the delivery end of the platform 8 of the feed-table is the top or upper guide 23, which terminates at its delivery end beyond the said needle and at the periphery of the 55 toothed feeding-wheel 36, as shown in Fig. 3. The butt-board 23' is arranged longitudinal of the feed-table and perpendicular thereto, thus forming a wall against which the butts of the sheaves of flax to be operated upon 60 are pressed in order to effect an approximate adjustment and evening of the straws when they are placed upon the table and before being engaged by the grasping-chain 6. The guide 23, the board 23', and the feed-table 8 65 may be regarded as elements which consti-

tute the guide for the straw and collectively form the straw passage-way.

Arranged at the rear end of the feed-table and transversely relative thereto is the vibrating needle-frame B, the principal novel feature of this invention. This needle-frame consists, preferably, of two arms 24, slightly divergent inwardly and rigidly connected at their convergent ends by means of the castings 25 and 26, the connections being 70 effected by the yoke-bolts 24', as clearly indicated in Fig. 2. The casting 25 is provided with a centrally-arranged bearing which journals upon the shaft 27, this shaft being supported in suitable brackets upon the frame 80 of the machine, thus affording a pivotal support for the outer end of the needle. The needle is therefore free to vibrate to a limited extent in a vertical plane, and motion is communicated to it in the following manner: A 85 transversely-extending shaft 28, driven from any convenient part of the machine, has on its forward end the crank-disk 29, provided with the wrist-pin 29'. A pitman 30 connects the said wrist-pin with the casting 26. 90 In order to render the pitman connections universal, and thus provide for transverse lateral movement of the lower end thereof, such movement being required in consequence of its vibrating about the shaft 27 as 95 a center, the said connections between the casting 26 and the wrist-pin 29' are effected by means of the journal-boxes 31 and 32, respectively, as clearly shown in the several figures. The extent of the vibratory movement imparted to the needle will depend either upon the throw of the wrist-pin 29' on the crank-disk 29 or upon the distance of the casting 26 with its bearing from the pivotal center of the needle, the movement in either 100 event being sufficient to vibrate the free ends of the arms a distance substantially equal to the depth of the straw passage-way.

The arms 24 of the needle are constructed of pipes tapered as shown, on the free ends of which are fixed the rectangular blocks 24². To these rectangular blocks are secured, by the bolt 33', the opposing needle-points 33, the construction of which points is set forth in Fig. 5. These needle-points are arcuate 115 in form, the center of their curvature being coincident with the center of vibration of the needle-arms. The needle-points are arranged some distance apart, leaving the gap 34 therebetween. The arrangement of this gap 34, the needle-points 33, and the pivotal center of the needle itself is made symmetrical with respect to a horizontal line passing through the center of the straw passage-way midway between the guide 23 and the floor 8 of the 120 feed-table, so that the gap between the said points is made to traverse the height of said passage-way. It is manifest that the amount of straw forced past the needle-points through the gap 34 will depend upon the extent of 125 130

said gap; the rapidity with which it is made to traverse the said straw passage-way, and the pressure with which the straw is forced against the said needle-points.

5 To prevent deflection of the free ends of the arms 24, due to the pressure of the straw against the needle-points, the guide-plates 35 are placed on both the front and rear sides of the free ends of said arms, the blocks 24² on 10 said arms contacting said guides.

In order to insure the straw being removed from the delivery side of the needle and passed to the grasping-chain 6, the toothed feeding-wheel 36 is interposed therebetween, 15 the said feeding-wheel having a diameter somewhat greater than the sprocket-wheel 5, upon which the grasping-chain is mounted and with which it is concentric. This enables the feeding-wheel to engage the straw 20 immediately upon its delivery from the needle and to force it on into engagement with the said grasping-chain, the guides 37 holding the straw in engagement with said wheel.

The operation of the machine will be readily understood. Bundles of flax-straw are placed upon the feed-table 8, the position of the butts being determined and evened up by the board 23', the bands having been severed. The straw is engaged about midway 30 of its length by the finger 11' of the feed-chain 11 and pressed forward beneath the guide 23 and against the needle-points 33. The needle-frame B is made to vibrate by the mechanism already described, which will 35 permit the straws which lie adjacent to said needle to be pressed through the gap 34 when said gap successively registers with their several positions. The manner in which the straws of flax are forced through the needle- 40 gap 34 will be apparent from an inspection of Fig. 3^a. In this figure the small circles represent sections of individual straws, and, as before explained, the fingers 11' of the feeding-chain exert a pressure upon the straws

45 tending to press them against the needle-points. The said gap 34 between the needle-points will move successively past the straws which lie adjacent to the points of said needle, these straws being indicated by the letters *a b c d e*, &c., and when the gap between the points of the needle registers with any one of these particular straws—as, for instance, *e*—this straw *e* will be forced through the gap. Simultaneously with their 50

55 passing through the gap the gap will have moved to a new position and the pressure on the straws will bring others to occupy the place formerly occupied by the straws which have passed through the gap. As soon as

60 the straws pass the needle-points they are no longer subjected to any appreciable pressure, and the tapered needle-points 33 will cause the straws to be forced toward the feeding-wheel 36. The feeding-wheel will then engage the straws and will not permit them to

again occupy a position adjacent to the points. As the movement of the needle is comparatively rapid, the angle of the needle will thus exert a constant tendency to force the straw onward in its movement in the direction of said feeding-wheel. In practice the needle-points are made about three thirty-seconds of an inch apart, thus giving the gap a width of three thirty-seconds of an inch. The average diameter of flax-straw is 70 about one-sixteenth of an inch, some of course exceeding this and some falling below; but the width of the gap is such that only one straw of an average size is permitted to pass therethrough at once; but where two did not 75 exceed three thirty-seconds of an inch they could both pass through the gap abreast of each other. The result is that a sheet of straw of a single straw in thickness is fed through the feeding mechanism to the feeding-wheel, which will result in a very uniform flow of fiber from the delivery end of the machine. The arrows in Fig. 3^a indicate the direction in which the pressure bears upon the individual straws. As the straw passes 80 through the gap in the needle-frame it is immediately engaged by the toothed feeding-wheel 36, which forces it forwardly into engagement with the grasping and conveying chain 6. After being engaged by this chain 85 6 the straw is operated upon by the breaking and scutching mechanism which, as before intimated, is not material in this connection. If it is desired to increase the quantity of straw admitted through the gap, the lever 19 90 is dropped, compressing the spring 17, which will increase the driving efficiency of the friction-disks 13 and 14, and thus increase the pressure brought to bear by the feeding-chain 11 upon the straw in front of the needle-points 33. To secure a lighter feed, the 95 above operation is reversed.

What I claim as my invention, and desire to secure by Letters Patent, is—

1. In a feeding mechanism for flax-brakes, 110 in combination, guiding means for the straw, said guiding means forming a straw passage-way, a device provided with opposing points having a gap therebetween, said points being arranged to traverse said straw passage-way, actuating means for said device, and means for pressing the material into said passage-way and against said points, substantially as set forth.

2. In a feeding mechanism for flax-brakes, 120 in combination, guiding means for the straw, said guiding means forming a straw passage-way, a device provided with opposing points having a gap therebetween, the said points being arranged to traverse said straw passage-way, actuating means for said device, and yieldingly-driven means for pressing the material into said passage-way and against said points, substantially as set forth.

3. In a feeding mechanism for flax-brakes, 130

in combination, guiding means for the straw, said guiding means forming a straw passage-way, a vibrating needle-frame provided with opposing points having a gap therebetween, 5 the said points being arranged to traverse said straw passage-way, means for vibrating said needle-frame, and means for pressing the material into said passage-way and against said needle-points, substantially as set forth.

4. In a feeding mechanism for flax-brakes, in combination, guiding means for the straw, said guiding means forming a straw passage-way, a yieldingly-driven feeding-chain operating 15 in said passage-way, a vibrating needle-frame provided with opposing points having a gap therebetween, said points being arranged to traverse said straw passage-way near the delivery end thereof, and means for 20 actuating the said needle-frame, substantially as set forth.

5. In a feeding mechanism for flax-brakes, in combination, guiding means for the straw, said guiding means forming a straw passage-way, a vibrating needle-frame provided with 25 opposing points having a gap therebetween, said points being arranged to traverse said straw passage-way near the delivery end thereof, means for actuating the needle-frame, yieldingly-driven means for pressing the material into the straw passage-way and 30 against the points of said needle-frame, and a toothed feeding-wheel located at the delivery side of said needle-points for receiving 35 the material therefrom and passing it for-

ward to the machine, substantially as set forth.

6. In a flax-brake, in combination, a feed-table, an upper guide and a butt-board which together form a straw passage-way, a yieldingly-driven feed-chain in said passage-way, a vibrating needle-frame arranged to traverse said passage-way near the delivery end thereof, a grasping and conveying chain, and a toothed feeding-wheel arranged to deliver 40 the material from the said needle-frame to the said grasping and conveying chain, substantially as set forth.

7. In a feeding mechanism for flax-brakes, in combination, guiding means for straw, 45 said guiding means forming a straw passage-way, a yieldingly-driven feed-chain in said passage-way, a vibrating needle-frame arranged to traverse said passage-way near the delivery end thereof, the said needle comprising two arms rigidly secured together at 50 their outer ends and pivotally mounted on the frame of the machine, needle-points placed in opposition to each other at the free ends of said arms and with a slight gap therebetween, the said gap arranged to come within 55 said passage-way, means for vibrating said needle-frame, and a toothed feeding-wheel for receiving the material from said needle-points and conveying it therefrom, 60 substantially as set forth.

GEORGE H. ELLIS.
